(57) **CLAIM**

The ornamental design for a removable grip for shopping bag handles, as shown and described.

DESCRIPTION

FIG. 1 is a perspective view of the top, left side, and front of a removable grip for shopping bag handles in accordance with my new design;

FIG. 2 is a top plan view of the removable grip shown in FIG. 1;

FIG. 3 is an elevational view of the front of the removable grip shown in FIG. 1, the rear being identical thereto;

FIG. 4 is an elevational view of the left side of the removable grip shown in FIG. 1, the right side being identical thereto; and,

FIG. 5 is a bottom plan view of the removable grip shown in FIG. 1.
